UNITED STATES PATENT OFFICE.

ALEXANDER WINK GRANT, OF MOUNTAIN LAKES, NEW JERSEY.

FOUNTAIN MOP.

Application filed September 21, 1925. Serial No. 57,671.

This invention refers to mops for washing automobiles, carriages and other objects which it is desirable to wipe over with a constant supply of water for slushing the 5 surface and removing grime and dust.

The primary object of the invention is to achieve in one article, a constant sluicing water supply as from a hose-pipe and the wiping action of a hand mop, characterized 10 by the absence of rigidity and adaptability of the latter to be wrapped over, around and into the multitudinous contours, angles and corners of an automobile or the like being washed.

15 Another object is to simplify the construction of a fountain mop.

The above with additional objects and advantages will be hereinafter more fully described in the following specification and 20 particularly pointed out in the appended claims.

For full comprehension, however of the invention reference should be had to the accompanying drawings forming a part of this 25 specification, in which the same reference characters indicate the same parts and wherein:—

Fig. 1 is a perspective view of a mop constructed in accordance with my invention;

30 Fig. 2 is a view of the mop head or bag opened up to disclose the interior;

Fig. 3 illustrates a modification in section, and

Fig. 4 shows the manner in which the mop 35 may be handled when washing objects capable of being wrapped over or around.

Referring now to the drawings, 2 indicates a backing or mop head comprising a flat, preferably rectangular water bag or 40 container composed of fabric such as duck, rubberized duck or other flexible impervious material. The top side of the bag has a water supply pipe leading therethrough, preferably near the middle, to the interior, the bottom side being perforated at 4 at 45 suitably arranged points over its area to allow the water to jet out in small flows effectively distributed between the edges of the mop.

50 As shown particularly in Fig. 2, the mop head or bag can be made of sheets of flexible impervious material 5 stitched together around the edges to form the bag with a reinforcing fabric lining 6, the bottom of the bag being provided with a series of perforations 4 and the mopping surface being

constituted by tufts of string 7 secured in rows between the perforations by tapes 8 stitched or otherwise suitably fastened to the bottom surface of the bag. 60

The water supply pipe is coupled to the mop head or bag by a metallic nipple 9 having its inner end flanged at 10 to overlie a portion of the interior surface of the top of the mop head or bag, a rubber washer 11 65 being disposed between the interior of the bag and flange to prevent leaking at the joint. If desired the flange 10 may be given a protective coating (not shown) of rubber applied in liquid form and allowed to 70 solidify.

If desired the nipple may be in the form of a hose length 13 forming a handle, see Fig. 3, passed through the top of the mop head or bag and held in place by a collar 75 15 on the end of the hose length and a cup-shaped collar 14 of rubber or other flexible material which closely encircles the hose exteriorly of and adjacent to the bag. The cupped form of the collar enables it to be 80 flexed forward from the dotted position to the full position so that it clamps down about the juncture of hose and mop head or bag and forms a tight joint.

The disposition of the water supply at 85 the side of the mop head or bag opposite to the perforations promotes a strong direct flow of water from the supply to the perforations or orifices and in use the water bag establishes a constant water sluice and provides a soft yielding backing with sufficient 90 substance to effectively wipe plane surfaces without sacrifice to its capability to be inserted into acute angles or wrapped about the more inaccessible portions such as wheel 95 spokes and the like. Fig. 4 illustrates the manner in which the bag or mop may be wrapped around a part of an automobile, a spoke for instance, to enable intimate sluicing and wiping thereof. 100

What I claim is as follows:—

1. A fountain mop comprising a flexible impervious bag having a perforated surface at one side and a water supply pipe leading into the interior of the bag from the opposite side thereof and a mopping element attached to said bag about said perforated surface. 105

2. A fountain mop comprising a flat flexible closed bag having a perforated cleaning 110 surface at one side and a metallic nipple passed through the opposite side of the bag,

- the interior end of the nipple being flanged and clamped against the inner side of the bag and a rubber washer disposed between the side of the bag and the flange.
- 5 3. A fountain mop comprising two rectangular sheets of impervious fabric stitched at their edges to form a bag, one of the sheets being provided with a series of perforations, tufts of string arranged in rows 10 at the sides of the perforations, tapes extending over the tufts and stitched to the perforated sheet to form a mopping surface, and a water supply pipe leading into the interior of the bag.

4. A fountain mop comprising two rectangular sheets of impervious fabric stitched at their edges to form a bag, a fabric lining for the interior surface of the bag, one wall of the bag being provided with a series of 15 perforations, tufts of string arranged in rows 20 at the sides of the perforations, tapes extending over the tufts and stitched to the perforated sheet to form a mopping surface, and a water supply pipe leading into the interior of the bag.

In testimony whereof, I have signed my name to this specification.

ALEXANDER WINK GRANT.
